UNITED STATES PATENT OFFICE.

JACKSON G. WILLIAMS, OF COUNCIL BLUFFS, IOWA.

VENTILATOR.

Application filed April 9, 1921. Serial No. 460,141.

To all whom it may concern:

Be it known that I, JACKSON G. WILLIAMS, a citizen of the United States, residing at Council Bluffs, in the county of Pottawattamie and State of Iowa, have invented certain new and useful Improvements in Ventilators, of which the following is a specification.

The present invention relates to improvements in ventilators, and it more particularly refers to a simple and inexpensive ventilating device adapted to be attached to the sashes of windows for the purpose of at all times supplying fresh air in suitable quantities to the room in which the window is placed.

An object of the invention is to provide an improved ventilator for permitting air to circulate freely into and out of the rooms of dwelling houses and the like and in which an accurate control of the amount of such air is provided.

A further object of the invention lies in providing a ventilator of the character above indicated in which the parts are susceptible of attachment to the usual form of window sash without any material modification of the construction thereof except to provide suitable passages therethrough for the amount of the air currents.

With the foregoing and other objects in view, the invention will be more fully described hereinafter, and will be more particularly pointed out in the claims appended hereto.

In the drawings, wherein like symbols refer to like or corresponding parts throughout the several views,

Fig. 1 is a fragmentary view of a building with a window equipped with an improved ventilator constructed according to the present invention;

Fig. 2 is an enlarged fragmentary view of the same;

Fig. 3 is a horizontal sectional view taken on the line 3—3 in Fig. 2; and

Fig. 4 is a vertical sectional view taken on the line 4—4 also in Fig. 2.

Referring more particularly to the drawings, 5 represents a wall of a building such as a dwelling house, factory or other enclosed place requiring ventilation, 6 the window

casing or frame, and 7 the usual vertically reciprocating sash.

In accordance with the present invention 55 the improved ventilating device is mounted directly in the sash 7, and for this purpose I initially form transversely through one rail of the sash a pair of openings 8 and 9 which open on the exterior into a casing 10 60 provided with flanges 11 to receive screws or other fastenings 12 by which the casing is secured to the outside face of the window sash 7. The casing 10 is preferably an elongated, substantially narrow construction of 65 only a slight depth necessary to house the various pieces of apparatus and to permit them to properly function, but the housing 10 will in no way detract from the appearance of the building or window and will 70 not impede the free movement of the sash.

In the front wall of the casing 10 I provide a pair of perforations 13 and 14 which are preferably placed directly in front of the openings 8 and 9 in the sash 7. Immediately within the casing 10 and reciprocating in contact with the front wall thereof is a slide plate 15 also formed with apertures 16 and 17 of substantially the same size as the perforations 13 and 14 whereby the two sets 80 of perforations and apertures may be brought into complete registry, for instance when the slide plate 15 is moved to its final position at the left. Of course an adjustment of the plate 15 toward the right will 85 effect a greater or less closure of the perforations and apertures.

A bar 18 projects outwardly from the plate 15 through the perforations 13 and 14 and is equipped with a thumb or finger piece 90 19 to aid in the shifting of the plate. A screen 20 is secured to the interior face of the plate 15, covering the apertures 16 and 17 in order to prevent insects from getting into the casing 10 and finally into the room. For 95 this purpose also the openings 8 and 9 in the window sash 7 may be covered with mesh 21 carried by a plate 22 secured by screws or other fastenings 23 to the interior face of the window sash 7.

The casing 10 forms a housing for a leaf 24 which extends substantially the full length of the casing and is also substantially of the same height as the casing ex-

cept that the ends of said leaf 24 are removed on diagonal lines 25 and 26 to provide suitable spaces for the passage of the air. It will be noted that these removed parts of the leaf 24 are at the ends of the casing and out of line with the perforations and apertures so that the incoming draft is required to take a zig-zag or circuitous course in getting into the room. This will 10 effectively arrest any undue rushing of air currents and will provide for the even and uniform distribution of the air into and out of the room.

As seen in Fig. 4, the leaf 24 normally rests in a forwardly inclining position by reason of a weight 27 which reposes in the forwardly upturned flange 28 along the lower edge of the leaf. The weight 27 is, in practice, furnished by dropping solder 20 in suitable quantity upon the flange. The leaf 24 swings back and forth in a direction at right angles to the plane of the leaf, the flange 28 being rounded at its bottom in order to facilitate this oscillating motion. 25 The lower end of the leaf is close to the outer face of the window sash 7 so that currents of air of unusual velocity rushing into the casing 10 will strike the leaf 24 and swing it automatically on its rounded 30 bottom portion and cause it to close against the passages 8 and 9. In this way, when high winds arise, storms or the like, the leaf 24 will close and prevent the entrance of ventilation at this time. When, however, 35 the storm subsides, the leaf 24 will again spring forwardly and the more gentle air currents may then enter about the sides of the plate. The device therefore provides both an automatic adjustment of the ventilation through the oscillating leaf 24 and also a manual adjustment through the plate 15 which is set by hand and may be changed from time to time during various seasons of the year.

40 45 The device will be employed in numbers on the windows of rooms for the purpose, not only of allowing air to enter, but also to allow of the removal of air which has become heated, and for this purpose one 50 of the devices for instance may be placed on the lower rail of the lower window sash, while another device is placed as shown in the drawings on the top rail of the upper sash.

55 I do not wish to be restricted to the size, form, and proportions of the various parts, and obviously changes could be made in the construction herein described without de-

parting from the spirit of the invention, it being only necessary that such changes fall 60 within the scope of the appended claims.

What is claimed is:—

1. A ventilator for window sashes and the like having openings made therethrough, comprising a relatively shallow 65 and elongated casing with its rear side open and placed against the sash about the openings, means to secure the casing to the sash, said casing being tightly closed at its sides and provided with perforations in its 70 front wall spaced from, but in alinement with, the openings in the sash, a plate within the casing slidably fitted against the inner face thereof, said slide plate provided with mesh-covered apertures adapted to 75 register with the perforations in the front wall of the casing, a yoke piece on the plate having arms extending outwardly through the perforations in the casing and having an operating piece lying in front of the 80 casing, and a leaf having a flange at its base portion projecting forwardly and providing a rounded under-surface upon which the leaf is adapted to rock, said flange being weighted to normally incline 85 the leaf toward the front part of the casing, said leaf having cut-away portions at its ends.

2. A ventilator for sashes having spaced-apart openings therethrough comprising a 90 screen secured to the inner face of the openings, a thin narrow flanged casing secured to the outer surface of the sash about the openings and provided with a front wall, having perforations lying in front of the 95 openings in the sash, a slide plate moving longitudinally within the casing against the front wall thereof to mask the perforations, said plate having apertures to aline with the perforations, a screen placed over 100 the perforations and carried by the plate, a yoke piece extending through the apertures connected with the plate for shifting the same, and a leaf extending substantially the height of the casing and adapted to rock 105 within the casing and having a lower round portion for supporting the leaf, said leaf being weighted to incline forwardly and having cut-away portions at its ends.

In testimony whereof, I have affixed my 110 signature in presence of two witnesses.

JACKSON G. WILLIAMS.
